(30) **Foreign Application Priority Data**

(57) **CLAIM**

Mar. 20, 2003 (JP) 2003-007600

We claim the ornamental design for an electronic information displaying device, as shown and described.

(51) **LOC (8) Cl.** **14-02**

DESCRIPTION

(52) **U.S. Cl.** **D14/345**

FIG. 1 is a top perspective view of an electronic information displaying device of the present invention in an opened position;

(58) **Field of Search** D14/341-346;

FIG. 2 is a front view thereof;

D18/1, 2, 7; 235/145 A, 145 R; 341/22,

FIG. 3 is a rear view thereof;

23; 345/156, 168, 169, 172, 173, 87; 349/12;

FIG. 4 is a first side view thereof;

361/680-686; D19/60; 434/201; 708/105

FIG. 5 is a second side view thereof;

(56) **References Cited**

FIG. 6 is a top view thereof;

U.S. PATENT DOCUMENTS

FIG. 7 is a bottom view thereof; and,
